CHARLES A. ERICKSON, OF LOS ANGELES, CALIFORNIA.

GASIFYING DEVICE FOR LIQUID FUEL.

1,117,354.

Specification of Letters Patent.

Patented Nov. 17, 1914.

Application filed May 23, 1914. Serial No. 849,641.

To all whom it may concern:

Be it known that I, CHARLES A. ERICKSON, a citizen of the United States of America, residing at Los Angeles, county of Los Angeles, State of California, have invented a certain new and useful Gasifying Device for Liquid Fuel; and I do hereby declare the following to be a full, clear, and exact description of the invention, such as will enable others skilled in the art to which it appertains to make and use the same.

This invention relates to gasifying devices for liquid fuel, and it may be said to consist in the provision of the novel and advantageous features and in the novel and improved construction, arrangement, and combination of parts as will be apparent from the description and claims which follow hereinafter.

One object of the invention is to provide a novel and improved device which is adapted to gasify liquid fuel; thus permitting the use, with good results, of the heavier and comparatively cheaper grades of liquid fuel—such as distillate and kerosene—to operate ordinary internal combustion motors.

Further objects of the invention are to provide a novel and improved device of the nature specified which is simple in construction and cheap to manufacture, readily applied to ordinary internal combustion motors, economical to install, maintain, and use, and effective in action.

Other objects and the advantages of the invention will be apparent to those skilled in the art from a careful consideration of the following description of the preferred construction of the device, taken in connection with the accompanying drawings in which—

Figure 1 shows the device applied to an automobile motor; Fig. 2 is an elevational view of the device; Fig. 3 is a plan view of the device; Fig. 4 is a longitudinal sectional view taken on the line 4—4 of Fig. 3; Fig. 5 is a cross-sectional view taken on the line 5—5 of Fig. 2; Fig. 6 is an elevational view of the heat distributing member; Fig. 7 is a top plan view of the same, and Fig. 8 is a bottom plan view of the same.

The shell 10 is made of suitable metal and has a portion 11 thereof threaded so that it may be screwed into the cylinder 12 or exhaust manifold of the motor; it being preferably screwed into the opening usually provided in the head of the cylinder for the release cock or for the valve cap. Within the shell 10 is arranged a heat distributing member consisting of a stem or core 13 having thereon substantially radial fins or flanges 15 which latter are provided with openings 14 in the lower part thereof and adapted to contact with the interior wall of shell. The heat distributing member is preferably made of copper in order that it may have a high degree of heat conductivity. The shell 10 is provided with an inlet orifice 15' at the top part thereof, and with an outlet orifice 16 at the bottom part thereof. The inlet orifice 15' may be suitably connected with the source of liquid fuel, and the outlet orifice 16 may be connected by suitable piping 17 to the carburetor 18. A plug 19 is screwed or otherwise detachably fitted into the top part of the shell 10 to permit of the heat distributing member being easily inserted into or removed from the shell.

From the foregoing it will be understood that a part of the heat generated in the cylinder 12—due to combustion of the liquid fuel—is conducted through the shell 10 and the heat distributing member and by them imparted to the liquid fuel to cause the latter to gasify as it flows through the shell upon the suction stroke of the motor.

I claim:

1. The herein-described device for gasifying liquid fuel, consisting of a shell having a portion thereof threaded for attachment to a motor, said shell provided with an inlet orifice and with an outlet orifice, a plug removably fitted in the shell, and a heat distributing member arranged within the shell.

2. The herein-described device for gasifying liquid fuel, consisting of a shell having a portion thereof threaded for attachment to a motor, said shell provided with an inlet orifice and with an outlet orifice, a plug removably fitted in the shell, and a heat distributing member arranged within the shell.

and comprising a core having thereon substantially radial flanges provided with openings and adapted to contact with the interior wall of the shell.

5 In testimony whereof I have signed my name to this specification in the presence of two subscribing witnesses at Los Angeles.

county of Los Angeles, State of California,
this 14th day of May A. D. 1914.

CHARLES A. ERICKSON.

Witnesses:

A. H. LIDDERS,
ELLA SCOTT.
